OF GRENWOLDE, GREAT NECK, NEW YORK

AIRPLANE

Application filed October 4, 1928. Serial No. 310,370.

This invention relates to aircraft and particularly airplanes.

It is the practice in the construction of airplanes to cushion or pad certain parts of the cockpit or personnel compartment to avoid injury to the pilot in the event of being thrown violently thereagainst, and it is particularly important in high powered or high speed machines, or machines which are catapulted into the air to construct the back of the cockpit, and especially the upper part thereof, in the form of a soft cushion or pad to cushion the impact of the pilot resulting from the high acceleration which is given to the craft, as for example during the launching into the air by catapulting. This padded rear part of the cockpit, however, offers the disadvantage that it must be built high enough to reach beyond or to the level of the head, and accordingly, as ordinarily constructed and arranged, it is an impediment to the ingress and egress of the pilot from the cockpit and tends to obstruct the rear view. Ready ingress and egress and an unobstructed view are particularly important in military and naval craft. The object of the invention is an airplane in which the padded or cushioned part of the cockpit, while formed as a rigid part thereof, is nevertheless capable of being readily swung over laterally of the body or fuselage to a point within the cockpit where after the craft is catapulted into the air it is entirely out of the way and forms no impediment to either the egress from the craft or to the vision. A further object is a construction of this general character possessing the qualities of simplicity of construction, lightness in weight and ready and easy manipulation by the pilot either during flight or at rest.

For a better understanding of the invention reference may be had to the accompanying drawings wherein—

Fig. 1 illustrates a perspective view of a

part of a fuselage and cockpit of an airplane embodying the invention;

Fig. 2 is a transverse secondary view through the cockpit showing the particular manner of constructing and mounting the cushioning means thereupon; and

Fig. 3 is a view taken at right angles to Fig. 2.

Referring to the drawings, I have illustrated my invention as embodied in the fuselage of an airplane, the frame of the fuselage including upper longérons 1, vertical posts or members 2 and transverse horizontal members 3, these parts being as for example, of standard tubular form and defining a cockpit or pilot's compartment in which is disposed a seat 4 and the various control mechanisms, which need not be described since they may be of any and usual construction. The cushioning means against which the body is thrown during the rapid acceleration of the craft upon being catapulted into the air, instead of being built in to form an immovable part of the rear wall of the cockpit, is in the form of a laterally movable and disappearing device 5, the latter being carried on the free end of a support tube 6 which in the operative position projects upwardly to support the device 5 substantially in line with the head of the pilot, this support tube 6 having its free end formed into a forwardly projecting bend 7 to bring the device 5 into position to perform its function of receiving and cushioning the head of the pilot when the craft is catapulted. The cushioning means 5 and its support tube 6 are rigidly carried in a transverse plane by means of the cross tubular frame member 3 of the fuselage disposed at the rear of the cockpit, the support tube 6 being attached thereto by the collar 8 which is welded to the tubular frame member 3 and is provided with the upwardly projecting rigid lugs 9 to form a fore and aft pivotal axis 10 for the lower end of the support tube 6, the latter being journaled between

the upwardly projecting lugs 9 on the axis 10 for lateral swinging movements in a plane transverse to the fuselage or in the plane of the cross member 3. The tube 6 with the cushion means 5 is locked in a substantially vertical position by means of a pair of spring clips 11 or jaws which form a part of a collar 12, welded also to the cross tube 3 in spaced relation to the collar 8, the tubular support 6 having a tubular arm 13 as a cooperating locking member projecting outwardly from adjacent the journaled end thereof in the plane of lateral movement, and being automatically engaged by the spring clips 11 when the cushioning means is thrown to the operative position. The locking member 13 approximates a right angular relation with the tube support 6, making therewith slightly less than a right angle. The fuselage cowl ing is indicated diagrammatically at 14, and the arrangement is such that the cushioning means 5 may be thrown over into the dot and dash position indicated in Fig. 2 entirely within the cockpit and without fouling any part of the fuselage, the engagement and disengagement between the arms 13 and the spring locking clips 11 being automatically effected by the manipulation of the spring cushioning means 5, and thus enabling the pilot to manipulate the spring cushioning means with great facility while either at rest or in the air. The cushioning means 5 may be of any suitable form and construction, but in the particular embodiment shown it comprises an annular former block 15, the disc 16, a suitable covering 17, as for example of leather, and a cushioning hair material or the like 18, the whole being secured to the forwardly bent part 7 of the tubular support by means of screws 19 passing through the plate 7' which is welded to the tube part 7, and entering the former blocks 15.

As above indicated, a cockpit cushion of the character described, has marked advantages over the usual form of cockpit cushion. It can be readily swung over laterally in planes transverse to the fuselage to either disappear therewithin, or to assume a substantially vertical or operative position. It is rigidly supported in the operative position and is of minimum weight and simple construction. In the swung over position it permits the ready ingress and egress of the pilot and leaves an unobstructed vision towards the rear, and it is entirely effective in preventing injury to the pilot upon rapid acceleration of the craft during the catapulting and other operations resulting in such acceleration.

I claim:

60 1. In an airplane a fuselage having a cockpit therein and a retractable cushioning means disposed in the cockpit, said cushioning means tending to obstruct the ingress and egress of the personnel while disposed in the 65 operative position and means for readily re-

tracting the cushioning means to a non-ob structing position at the will of the personnel.

2. An airplane including a personnel compartment with cushioning means mounted firmly and unyieldingly in the fore and aft direction at the back of said compartment, but operable laterally to a retracted position within the compartment.

3. An airplane of the character set forth in claim 2 wherein the cushioning means is supported substantially in line with the head of the pilot.

4. An airplane of the character set forth in claim 2 wherein the cushioning means in one position is mounted substantially in line with the pilot's head and is supported in a position to be engaged by the pilot's head upon rapid acceleration of the craft.

5. In an airplane a fuselage framework defining a personnel compartment, a cushioning means firmly supported by the fuselage frame substantially in line with the head of the pilot and pivotally mounted on said frame for lateral movement into a position out of line with the pilot's head.

6. An airplane of the character set forth in claim 5 wherein the cushioning means is carried by an elongated support which is pivotally mounted on the frame at the rear of the compartment for lateral movement in the transverse plane.

7. An airplane of the character set forth in claim 5 wherein means are provided for locking the cushioning means in one position.

8. An airplane of the character set forth in claim 5 wherein means are provided for spring locking the laterally movable cushioning means in a position substantially in line with the pilot's head.

9. In an airplane, a framework defining a personnel compartment including a transverse frame member disposed at the rear of the compartment, an elongated support pivotally supported by said transverse frame member for movements in the plane of the member, said elongated support being bent forwardly and carrying cushioning means thereon.

10. An airplane of the character set forth in claim 9 including a seat suitably supported within the compartment with the cushioning means projecting over the back thereof.

11. In an airplane of the character set forth in claim 9, wherein a snap spring catch is carried by the transverse frame member and the elongated support carries near its pivoted end a rigid arm engaging with said spring catch when the cushioning means is in operative position.

12. An airplane of the character set forth in claim 1 including means for locking the cushioning means in the operative position.

13. An airplane of the character set forth in claim 1 wherein the cushioning means may

be locked in its operative position and is supported in a position to receive the head of the pilot.

14. In an airplane a fuselage having a cockpit therein and a retractable cushioning means disposed in the cockpit, said cushioning means tending to obstruct the ingress and egress of the personnel while disposed in the operative position and means for readily re-
10 tracting the cushioning means to a non-ob- structing position within the confines of the cockpit at the will of the personnel.

In testimony whereof, I have signed my name to this specification.
